UNITED STATES PATENT OFFICE

153,342

DESIGN FOR A COFFEE MAKER

Joseph E. Fishelson, Wooster, Ohio, assignor to
The Duralux Company, Wooster, Ohio, a corporation of Ohio

Application May 14, 1947, Serial No. 139,037

Term of patent 14 years

(Cl. D44—26)

To all whom it may concern:

Be it known that I, Joseph E. Fishelson, a citizen of the United States, residing in Wooster, in the county of Wayne, State of Ohio, have invented a new, original, and ornamental Design for a Coffee Maker, of which the following is a specification, reference being had to the accompanying drawing, forming a part thereof.

Fig. 1 is a plan view of a coffee maker, showing my new design;

Fig. 2 is a side elevational view thereof.

I claim:

The ornamental design for a coffee maker, substantially as shown.

JOSEPH E. FISHELSON.
